UNITED STATES PATENT OFFICE

2,523,023

DIVIDED FRONT BRASSIÈRE

Hulda M. Ihnsen, Allentown, Pa., assignor to
Charis Corporation, a corporation of New York

Application June 29, 1948, Serial No. 35,899

1 Claim. (Cl. 2—42)

1
This invention relates to improvements in the type of brassière which controls both the bust and the diaphragm.

One of the drawbacks in the conventional brassière is that the diaphragm section, which must fit snugly to achieve control, tends to impede the free movement of the bust section during changes in posture. As the lines of the body in the front lengthen and shorten during changes in posture, the pull against the brassière will cause both the bust section and the diaphragm section to shift their position on the body, thus creating discomfort to the wearer and reducing the effectiveness of the diaphragm control.

In accordance with the present invention, I meet this difficulty by providing a diaphragm controlling member which underlies in part the bust member and which is detached along its top and bottom edges from the brassière proper. In such case the bust portion and the diaphragm controlling portion move independently of each other. Accordingly, the bust, being controlled solely by the bust controlling portion of the brassière, is free to move independently of the diaphragm which is controlled solely by the detached diaphragm controlling portion and in such case the diaphragm controlling member can be fitted tightly across the diaphragm of the wearer without impeding movement of the bust portion. Furthermore, since the detached diaphragm member underlies in part the bust member, control over the diaphragm is obtained over the entire diaphragm without interference with the bust portion.

A preferred form of this invention is shown in the accompanying drawing in which:

Fig. 1 is a front view thereof; and

Fig. 2 is a back or inside view thereof, partly broken away to show the relationship between the diaphragm controlling portion thereof and its bust controlling portion.

The garment herein claimed comprises a body portion 10 and two side panels 11 and 12 respectively, and it also consists of a bust controlling portion 13, a diaphragm controlling portion 14 and a pair of straps 15 and 16 respectively which are attached at their front ends to the bust controlling portion 13 and at their back ends to the back of the brassière. The brassière may also be provided with girdle connecting hooks 17 and 18 respectively which are shown to be attached to the diaphragm controlling portion of the brassière.

Both the bust controlling portion and the diaphragm controlling portion are attached along

2
their respective side edges to the body of the brassière and more particularly to its two side panels. A seam 20 is provided to attach the bust and diaphragm controlling portions to side panel 11 and a hook and eye construction 21 is used to attach said bust and diaphragm controlling portions to the opposite side panel 12. An elastic gusset 22 of triangular shape is interposed between the bust controlling portion and side panel 12.

Generally speaking, the diaphragm controlling portion 14 consists of a band which fits tightly across the diaphragm and which is sufficiently wide and strong so as to control the diaphragm. It may be provided with reinforcing bones or steels 25 which extend vertically thereof through its center portion. It is important to note that the upper portion of the member 14 is disposed in underlying relationship with respect to the bust controlling portion and that its lower portion extends downwardly, below the bust controlling portion, and as far as is needed to adequately cover the diaphragm. It may be found desirable to provide an elastic supporting member 26 which interconnects the top central portions of the bust and diaphragm controlling portions of the brassière but which does not interfere with the independent action of the diaphragm controlling portion. The bust member 13 carries a vertical seam 27 and a triangular seam 28 in each bust pocket.

It will be appreciated from the foregoing that the bust and diaphragm controlling members are completely free from rigid attachment to each other except to the extent that they are both attached to the side panels of the brassière. The bust controlling member can thus accommodate itself to a change in position without interfering with the position of the diaphragm controlling member on the body of the wearer. Accordingly, the present garment adequately controls the movement and position of the bust and at the same time it adequately controls the movement of the diaphragm. In view of the fact that the two controlling members are separate and independent from each other the action of the one does not in any way interfere with the action of the other. The bust and diaphragm controlling portions function in the manner of two separate garments, one constituting a brassière and the other a diaphragm band, but in accordance with the present invention they actually constitute integral parts of the same garment.

It will be appreciated from the foregoing that a preferred form of this invention has been shown

in the drawing and that this form may be modified and changed in many ways in accordance with individual requirements and practices within the broad scope and coverage of the invention.

I claim:

In a bust and diaphragm controlling garment having a bust member and a diaphragm controlling member attached at each side to corresponding side members which in turn are attached to a back member, the combination comprising a diaphragm member underlying in part the bust member and attached along each side to corresponding side members but detached along substantially the entire length of the top and bottom edges from the bust member and free from rigid connection therewith along such edges, said diaphragm member having its lower portion extending downwardly below the bust member so that it covers the diaphragm of the wearer, a bust controlling member which overlaps in part the diaphragm member and which is also attached to the side members, a central resilient connection between the bust controlling

member and the diaphragm member, said bust and diaphragm controlling members constituting the front of the garment and each being adapted to move independently of each other in accordance with the natural movement of the body, said bust and diaphragm members cooperating by means of their common points of attachment to follow the movement of the body parts supported thereby without chafing the body of the wearer and at the same time effecting complete support of the body portions in all positions.

HULDA M. IHSEN.
